UNITED STATES PATENT OFFICE.

VENCHEL J. TICHOTA AND AUGUST TICHOTA, OF DODGE, NEBRASKA.

DRAFT EQUALIZER.

Application filed June 11, 1921. Serial No. 476,766.

To all whom it may concern:

Be it known that we, VENCHEL J. TICHOTA, and AUGUST TICHOTA, citizens of the United States, residing at Dodge, in the county of Dodge, State of Nebraska, have invented a new and useful Draft Equalizer, of which the following is a specification.

This invention relates to draft equalizers and is more particularly designed as an improvement upon the structure disclosed in Patent No. 1,196,140 issued to us on May 12, 1914.

One of the objects of the invention is to strengthen the structure, render the mechanism more compact, and insure the proper operation of the parts under all conditions.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—

Figure 1 is a plan view of the equalizer. Figure 2 is a front elevation thereof. Figure 3 is a section on line 3—3, Figure 1. Referring to the figures by characters of reference 1 designates a clip adapted to be fastened to the tongue or other portion of the structure to be drawn and is provided with forwardly extending upper and lower arms 2 the forward ends of which are connected by a pivot bolt 3 on which is fulcrumed the inner end of a short lever 4. Arranged within the tongue 2 and back of the pivot bolt 3 is another pivot bolt 5 to which is connected one end portion of a long lever 6 there being wear plates 7 forming one end portion thereof and which engage the bolt 5. The plates are connected by a pivot bolt 8 and pivotally mounted on this bolt and between the plates is a lever 9 which extends transversely through the tongue 2 and between the bolts

3 and 5 and is connected by a link 10 to the lever 4. This link is adapted to receive a bolt 12 extending through the lever 4, there being a series of apertures 13 for the reception of the bolt, these apertures being provided in the lever 4. That portion of the lever 9 between the bolts 3 and 5 is curved or arcuate so as to allow for an extensive backward swinging movement of lever 9 without opposition from the bolt 5. A link 14 connects lever 9 to one arm of a bell crank 15 fulcrumed on the bolt 5. The other arm 16 of the bell crank works freely between stop pins 17 connecting the arms 2.

It has been found that by providing a structure such as described, a very compact arrangement is produced and the danger of the parts breaking is practically eliminated. As the bell crank 15 has a limited movement it is possible for the two levers 4 and 6 to have a limited independent movement, thereby to facilitate starting of a load. The parts can be readily adjusted to vary the distribution of the load, simply by shifting the position of the link 10 relative to the lever 4.

What is claimed is:—

A draft equalizer comprising a tongue including upper and lower members, a lever therebetween having limited relative movement, a short draft lever pivotally connected to the front end of the tongue, a long draft lever pivotally connected to an intermediate portion of the tongue, the two levers being extended in opposite directions, an equalizing lever pivotally mounted within the long draft lever and extending transversely through the tongue, a link connection between said equalizing lever and the short draft lever, a link connection between the equalizing lever and the first named lever.

In testimony that we claim the foregoing as our own, we have hereto affixed our signatures in the presence of two witnesses.

VENCHEL J. TICHOTA.
AUGUST TICHOTA.
